UNITED STATES PATENT OFFICE:

LEON LOBEL AND NORVIN FRANK, OF NEW YORK, N. Y., ASSIGNEES TO BELFRAN COMPANY, INC., A CORPORATION OF NEW YORK.

ARCH-SUPPORT.

1,129,039.

Specification of Letters Patent. Patented Feb. 16, 1915.

Application filed July 22, 1914. Serial No. 852,438.

To all whom it may concern:

Be it known that we, LEON LOBEL and NORVIN FRANK, citizens of the United States, and residents of the borough of Manhattan, city, county, and State of New York, have invented certain new and useful Improvements in Arch-Supports, of which the following is a specification, reference being had to the accompanying drawings.

10 The object of our invention is to provide a support for the arch of a foot having resilient properties adapted to perform a kneading or massaging office during the ambulatory movement of its wearer.

15 Referring now to the accompanying drawings, Figure 1, is a plan view of an arch support embodying our invention, partly broken away and partly shown in dotted lines to illustrate the elements composing

20 our preferred embodiment of the present invention; Fig. 2, is a vertical cross section taken at the line 2—2 of Fig. 1, and; Fig. 3, is a side view of Fig. 1, looking in the direction of the arrow of Fig. 2.

25 Referring now in detail to the drawings, 1 is a base plate in any suitable form, and which is adapted to lie adjacent to the inner sole of a shoe; 2 is a fan consisting of a plurality of fingers, and which is preferably

30 made of spring metal. This fan is fastened at one end in any suitable manner to the base plate 1, the fingers projecting therefrom in such contour so as to support the arch of a foot. Over this fan 2 is suitably

35 fastened to the base plate a covering 3 of leather or other suitable material. A spring alinement element 4 preferably substantially follows in contour the outline of the free ends of the fingers of the fan 2, which

40 spring alinement element is fastened by rivets 5 or otherwise to one or more of the central fingers of the fan. The ends of this spring alinement element 4 lie on the base plate 1, but are preferably not attached thereto thus insuring full free spring action therein.

We have also provided in our device a supplemental spring 6, one end of which is riveted or otherwise fastened to the base

50 plate by a fastening element 7, the other end

of which is bent upward and brought into loose contact with the spring alinement element 4.

It will be obvious from our construction as above described and shown, that the action of our arch support will be such when in operation to support the arch of a foot that, when in the act of walking, it will perform a constant resilient movement effecting a gentle massage to the foot, as well as giving great comfort to the wearer.

We have described and illustrated our preferred embodiment of this invention; but do not desire to be limited to the exact construction shown.

What we desire to cover by patent is set forth in the appended claims.

Claims—

1. In an arch support, a base plate, a fan having a plurality of fingers attached to said base plate, a spring alinement element attached to one or more of said fingers, said spring element also acting to keep said fingers in alinement, a supplemental spring attached to said base plate and adapted to support said spring alinement element, and a cover affixed to the upper side of said base plate so as to maintain the other elements thereof out of actual contact with a foot.

2. In an arch support, a base plate, a fan having a plurality of fingers attached to said base plate, a spring alinement element attached to one or more of said fingers, said spring element also acting to keep said fingers in alinement, and a supplemental spring attached to said base plate and adapted to support said spring alinement element.

3. In an arch support, a base plate, a fan attached to said base plate, a spring element attached to said fan, and a supplemental spring attached to said base plate and adapted to support said spring element.

4. In an arch support, a base plate, a fan having a plurality of fingers attached to said base plate and a spring element attached to one or more of said fingers, said spring element also acting to keep said fingers in alinement.

5. In an arch support, a base plate, a fan

attached to said base plate, a spring element attached to said fan, and a supplemental spring attached to said base plate and adapted to support said spring element.

5 6. In an arch support, a base plate, a fan having a web portion and a plurality of fingers extending therefrom, and a spring at-

tached to said base plate and adapted to support said fan.

LEON LOBEL.
NORVIN FRANK.
